UNITED STATES PATENT OFFICE.

JAMES F. CONNOR, OF CLEVELAND, OHIO.

CUFF LINK.

Application filed June 24, 1924. Serial No. 722,093.

To all whom it may concern:

Be it known that I, JAMES F. CONNOR, a citizen of the United States, residing at Cleveland, in the county of Cuyahoga and State of Ohio, have invented certain new and useful Improvements in Cuff Links, of which the following is a specification, reference being had to the accompanying drawings.

This invention relates to certain improvements in cuff links and it is an object of the invention to provide a novel and improved device of this general character comprising studs or heads connected in a manner whereby a cuff is effectively maintained in its proper position or in adjusted positions along the arm of a user.

Another object of the invention is to provide a novel and improved device of this general character wherein the studs or heads are connected in a manner whereby the same are automatically drawn one toward the other so that such action of the button will serve to tightly hold the cuff in desired position when the sleeve of a garment is drawn upwardly of the arm.

The invention consists in the details of construction and in the combination and arrangement of the several parts of my improved cuff link whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in end elevation of a cuff link constructed in accordance with an embodiment of my invention;

Figure 2 is a view in side elevation of the device as illustrated in Figure 1;

Figure 3 is an enlarged sectional view taken substantially on the line 3-3 of Figure 1;

Figure 4 is a sectional view taken substantially on the line 4-4 of Figure 3;

Figure 5 is a view in bottom plan of the stud or head member provided with the casing;

Figure 6 is a top plan view of the second head or stud as illustrated in Figures 1 and 2;

Figure 7 is a fragmentary view of the drum mounted within the casing.

As disclosed in the accompanying drawings, 1 and 2 denote studs or heads of desired dimensions, the head or stud 1 as herein disclosed being substantially flat and having affixed to its inner face a loop 3 which, when the device is in applied position, is adapted to be inserted through the buttonhole of a cuff.

The stud or head 2, as herein disclosed, is substantially conical in form and carried by said stud or head 2 is a cylindrical casing 4 the axis of which being perpendicularly related to the axis of the base of said stud or head 2.

The major portion of the casing 4 is contained within the stud or head 2 with preferably about a two-fifths portion of said casing extending beyond the base of the stud or head. This extended portion a of the casing 4 is adapted to be disposed through a buttonhole of the cuff when the device is in applied position.

Rotatably supported within the casing 4 is a hollow drum 5 about which is adapted to be wound a tape 6, said tape being preferably of metal although I do not wish to be understood as limiting myself in this respect as any other flexible member may be employed which can be used to advantage.

Contained within the drum 5 is a helical spring 7, the inner end portion of which being fixed to the shaft 8 upon which the drum 5 is mounted while the outer end portion of said spring is secured to the periphery of the drum 5. As herein disclosed, this connection of the spring with the drum is protected by cutting out a tongue 9 in the peripheral portion of the drum and bending said tongue inwardly of the drum for interlocking with the outer extremity of the spring.

Immediately adjacent to the resultant opening 10 provided by the tongue 9 the periphery of the drum 5 is provided with a second opening 11 and through said openings 10 and 11 is threaded an end portion of the tape 6 whereby said end portion of the tape is properly secured to the drum.

The tape 6 extends outwardly of the casing 4 through an opening 12 provided in the periphery of the extended portion of said casing and said tape has its outer end portion connected, as at 14, to the loop 3.

The extremities of the shaft 8 or those

portions thereof disposed through the side walls of the casing 4 are angular in cross section with the openings in the side walls of the casing similarly formed whereby said 5 shaft 8 is maintained against rotation.

The spring 7 operates to normally maintain the flexible member 6 retracted and wound upon the drum 5 so that the studs or heads 1 and 2 are normally in close contact 10 one with the other. By this means the cuff to which the link is applied is maintained in its proper position yet readily permitting the insertion or withdrawal of the hand through the cuff, the spring 7 readily permitting 15 the requisite separating movement of the heads or studs 1 and 2.

This connection between the studs 1 and 2 also permits the sleeve to be drawn upwardly of the arm to any desired height, the 20 pulling action of the spring 7 operating to maintain the cuff in close contact with the arm and thereby holding the sleeve in its desired adjusted position.

From the foregoing description it is 25 thought to be obvious that a cuff link constructed in accordance with my invention is particularly well adapted for use by reason of the convenience and facility with which it may be assembled and operated, 30 and it will also be obvious that my invention is susceptible of some change and modification without departing from the principles and spirit thereof and for this reason I do not wish to be understood as limiting 35 myself to the precise arrangement and formation of the several parts herein shown in carrying out my invention in practice except as hereinafter claimed.

I claim:—

40 1. A cuff link comprising in combination, a pair of heads, a casing carried by one of the heads with a portion of said casing extending beyond the base of the head and adapted for insertion through the button-

hole of a cuff, a spring drum mounted with- 45 in the casing, and a flexible connection between the spring drum and the second head, the casing being provided with an opening through which the flexible connection passes.

2. A cuff link comprising in combination, 50 a pair of heads, a casing carried by one of the heads with a portion of said casing extending beyond the base of the head and adapted for insertion through the button- 55 hole of a cuff, a spring drum mounted with- in the casing, and a flexible connection between the spring drum and the second head, the casing being provided with an opening through which the flexible connection passes, the axis of the casing being substantially 60 perpendicularly related to the axis of the base of the first named head.

3. A cuff link comprising separate heads, one of said heads being hollow and having 65 a portion thereof extending beyond the base of said hollow head and adapted for insertion through the buttonhole of a cuff, a flex- 70 ible connection between said heads, and spring actuated means for normally drawing said flexible connection into the hollow 75 head and retaining the heads normally in contacting engagement.

4. A cuff link comprising separate heads, one of said heads being hollow, a drum ro- 80 tatably mounted in the hollow head, a flex- 75 ible member winding upon said drum and extending exteriorly of the hollow head and connected with the second head, and cen- 85 trally located vertically disposed spring means yieldably holding the drum against rotation in one direction to normally hold the cord wound upon the drum with the heads in contacting engagement with each other.

In testimony whereof I hereunto affix my 85 signature.

JAMES F. CONNOR.
